UNITED STATES PATENT OFFICE.

EDGAR C. DAVIDSON, OF OGDENSBURG, NEW YORK.

SLIDE-VALVE GASOLENE-ENGINE.

1,167,547.

Specification of Letters Patent. Patented Jan. 11, 1916.

Application filed March 25, 1914. Serial No. 827,192.

To all whom it may concern:

Be it known that I, EDGAR C. DAVIDSON, a citizen of the United States, residing at Ogdensburg, in the county of St. Lawrence 5 and State of New York, have invented certain new and useful Improvements in Slide-Valve Gasolene-Engines, of which the following is a specification, reference being had therein to the accompanying drawing.

10 This invention relates to slide-valve gasolene-engines and has for its principal object the production of a simple means for controlling the admission of live gases into the explosive cylinder and also for controlling the discharge of the exhaust gases from the cylinder.

Another object of this invention is the production of a simple and efficient means for moving the valves longitudinally of the 20 cylinder so as to efficiently open and close the inlet and exhaust ports.

With these and other objects in view, this invention consists of certain novel constructions, combinations and arrangements of 25 parts, as will be hereinafter fully described and claimed.

In the drawings:—Figure 1 is a central vertical section of the valve and operating mechanism applied to the cylinder of an engine. Fig. 2 is a side elevation of the upper portion of the engine. Fig. 3 is a top plan view of the engine. Fig. 4 is a section taken on line 4—4 of Fig. 1, looking in the direction of the arrow. Fig. 5 is a detail perspective of the slide-valves. Fig. 6 is a sectional view showing the slide-valves in an open position. Fig. 7 is a side elevation of the cylinder-head removed from the cylinder of the engine. Fig. 8 is a fragmentary sectional 40 view taken through one of the sliding valves showing one of the parts formed therein.

By referring to the drawings, it will be seen that 1 designates the base of the engine, which carries the usual drive wheel 2. The 45 drive wheel 2 is carried by a shaft 3, which shaft carries a friction disk 4. The friction disk 4 engages the friction disks 5, which disks coöperate with the operating rods 4' for rocking the rocker-arms 5', as will be 50 more fully described hereinafter.

A cylinder casing 6 is mounted upon the base 1 and within the cylinder 6 a piston-head 7 is adapted to work, and is controlled by means of the piston-rod 8 which is connected to the drive wheel 2, as is common 55 with such engines. It should be understood

that any suitable operating means may be employed for reciprocating the piston 7 within the cylinder of the engine and operating the rods 4', without departing from the 60 spirit of the invention.

A cylinder-head 9 is carried by the cylinder 6 and is provided with a downwardly-extending sleeve 10, which sleeve is provided upon opposite sides thereof with circumferentially-extending slots 11, constituting the inlet and exhaust ports of the cylinder. The cylinder-head is also provided with a circumferential flange-portion 12 which overhangs the upper end of the cylinder, as is 70 clearly illustrated in Fig. 1, for the purpose of facilitating the attaching of the cylinder-head 9 to the body of the cylinder 6. The cylinder 6 is provided with inlet and exhaust nipples 13, to which may be connected 75 the ordinary exhaust conveying mechanism and also the carburetor, as is usual with such explosive engines. The cylinder-head 9 is, of course, provided with the usual socket 14 for the purpose of allowing a 80 spark plug to be inserted therethrough.

The cylinder 6 is provided with an off-set portion 15 at its upper end, and the sleeve-portion 10 of the cylinder-head 9 is spaced from the inner face of the off-set portion 15 85 of the cylinder 6 so as to allow the slide-valve 16 to efficiently operate between the sleeve 10 and the inner wall of the off-set portion 15 of the cylinder 6. Each of the slide-valves 16 comprises a substantially 90 semi-circular band having upwardly-extending threaded pins 17 formed thereon. These pins 17 extend up through the cylinder-head 9 and are connected to the transversely-extending eyes 18 of the rocker-engaging pins 95. A guiding sleeve 21 is formed around each of the pins 17 so as to constitute a guide for the pins 17 when the slide-valves 16 are reciprocated upon the cylinder 6. Each valve 16 is provided with a plurality of ports 100 22, which communicate with the upper edge of each slide-valve 16 and also with the inner face of the slide-valve for allowing air within the upper end of the cylinder to be forced down through the ports 22 and into 105 the cylinder 6 or out through the exhaust port formed in said cylinder and thereby prevent the compression of air by the reciprocation of the slide-valves.

A plurality of brackets 23 are supported 110 upon the cylinder-head 9 and the rocker-arms 5' are pivotally mounted upon the

brackets 23, as is clearly illustrated in Figs. 1, 4 and 6. The rocker-arms 5' pivotally engage the rocker-links 24 so as to allow the slide-valve 16 to be efficiently operated without binding as the operating-rods move relative to the cylinder 6.

From the foregoing description it will be seen that a very efficient and simple means has been produced for reciprocating the 10 slide-valve 16, relative to the cylinder 6 and thereby open and close the inlet and outlet ports 25 and 26, respectively. It should be further understood that the exhaust valve 16 will also have a very light load or strain 15 when starting to open, as the same will have the terminal pressure from the explosion stroke, which pressure will be immediately released upon opening the valve.

What I claim is:

20 1. A device of the class described, comprising a cylinder, said cylinder provided with inlet and exhaust ports, slide-valves adapted to open and close said ports, means for reciprocating said valves within said 25 cylinder, and said slide-valves provided with vertically-extending ports having laterally-extending discharge ports communicating therewith for preventing compression upon the top of said slide-valve as the same are actuated.

25 2. In a device of the class described, the combination of a cylinder, said cylinder provided with inlet and exhaust ports, a cylinder head carried by said cylinder, said cylinder provided with an off-set portion at its 30 upper portion, said head provided with a depending sleeve, said sleeve and off-set portion extending in parallel spaced relation, slide valves adapted to open and close said 35 ports, means for reciprocating said valves within the space between said sleeve and off-

set portion, and said slide-valves provided with vertically-extending ports having laterally-extending discharge ports communicating therewith, whereby air within the 45 space between said sleeve and said off-set portion will be forced through the ports formed in said slide-valves as said valves are actuated, whereby air compression upon the top of said slide-valves is prevented. 50

3. In a device of the class described, the combination of a cylinder, said cylinder provided with inlet and exhaust ports, slide-valves fitting upon said cylinder and conforming in shape thereto for opening and 55 closing said ports, means for reciprocating said valves, and said slide-valves provided with vertically-extending ports having laterally-extending discharge ports communicating therewith for preventing compression 60 upon the top of said slide-valves as the same are actuated.

4. In a device of the class described, the combination of a cylinder, said cylinder provided with inlet and exhaust ports, said cylinder having guide-portions, slide-valves slidably mounted within said guide portions for opening and closing said ports, said guide portions being adapted to retain said slide-valves in operative positions, means for reciprocating said slide-valves, and said slide-valves provided with vertically extending ports having laterally-extending discharge ports communicating therewith for preventing compression upon the top of said 70 slide-valves as the same are actuated. 75

In testimony whereof I hereunto affix my signature in presence of two witnesses.

EDGAR C. DAVIDSON.
